(57) **CLAIM**

The ornamental design for a kiosk as shown and described.

DESCRIPTION

FIG. 1 is a front perspective view of the claimed design for a kiosk, according to a first embodiment;

FIG. 2 is a front view of the claimed design of FIG. 1;

FIG. 3 is a rear view of the claimed design of FIG. 1;

FIG. 4 is a right side view of the claimed design of FIG. 1;

FIG. 5 is a left side view of the claimed design of FIG. 1;

FIG. 6 is a top view of the claimed design of FIG. 1;

FIG. 7 is a bottom view of the claimed design of FIG. 1;

FIG. 8 is a front perspective view of the claimed design for a kiosk, according to a second embodiment;

FIG. 9 is a front view of the claimed design of FIG. 8;

FIG. 10 is a rear view of the claimed design of FIG. 8;

FIG. 11 is a right side view of the claimed design of FIG. 8;

FIG. 12 is a left side view of the claimed design of FIG. 8;

FIG. 13 is a top view of the claimed design of FIG. 8; and,

FIG. 14 is a bottom view of the claimed design of FIG. 8. The ornamental design that is claimed is shown in the drawings as solid lines and surfaces having surface shading. The broken lines in the drawings are for illustrative purposes only and form no part of the claimed design. For example, broken lines formed by equal length dashes show unclaimed portions of the design.

1 Claim, 12 Drawing Sheets
